UNITED STATES PATENT OFFICE.

TOYOJIRO KATAYAMA, OF STANDARDVILLE, UTAH.

COAL AND ROCK SEPARATING MECHANISM.

Application filed March 7, 1924. Serial No. 697,640.

This invention relates to a method and apparatus for separating stone and slate from coal and particularly where the coal is broken into small sizes as is customary 5 at collieries.

In some collieries, at the present time, it is the custom to pass the coal on conveyors or chutes past pickers who, by hand remove the slate and stone as the coal passes them. 10 This method is not satisfactory for the reason that it is expensive and also for the reason that the human element enters too much into the efficiency of the work. In case of labor trouble, the efficiency of the work is 15 greatly impaired.

In other collieries, it is the custom to dump the coal into vats containing water, the coal being agitated under water, to cause the denser objects as rock and slate 20 to fall to the bottom thus causing the less dense coal to rise to the top. The coal is then taken off by suitable conveyors. This system is inadequate to meet the needs since it is expensive to operate and at some places, 25 water, in large quantities, is not available.

The primary object of my invention is the provision of an apparatus which will effectively remove the rock and slate from coal and which will be free of the human 30 element, cheap to operate and not expensive to construct.

Another object of my invention is the provision of a method of separating stone from coal wherein the mixture is dumped 35 from one conveyor to another conveyor arranged angularly to the first, the coal having a tendency to go to the far side of the conveyor to which it is delivered, the stone dropping on the near side, thereby separating 40 the coal and stone from each other, the stone and coal then being conducted to their respective piles.

Another and still further object of my invention is the provision of an apparatus for 45 separating stone and coal comprising a series of coacting conveyors, the arrangement of the conveyors being such that a conveyor delivering to another conveyor will be arranged at an angle thereto.

Another and still further object of my invention is the provision in such an apparatus of means for conducting the coal away 50 from the separating apparatus at the proper time.

Referring to the drawing where I have 55 illustrated an embodiment of my invention,

Fig. 1 is an elevation of an apparatus constructed according to my invention,

Fig. 2 is a cross section looking downwardly substantially on the line 2-2 of 60 Fig. 1 and showing the evolution of the distribution of the coal and stone as it passes through the several stages of separation.

Fig. 3 is a partial cross section looking downwardly substantially on the line 3-3 65 of Fig. 1 and showing the means for taking off the coal at the side of the conveyor B⁶.

Fig. 4 is a detail view of one of the conveyors,

Fig. 5 is a perspective view showing the 70 supporting means for the conveyor B¹¹ and the means for adjusting the angularity of the same,

Fig. 6 is a detail view showing the drive connections for one of the conveyors, the 75 gear housing cover being removed to show the interior thereof,

Fig. 7 is a diagrammatic view showing the 80 conveyor arrangement at the delivery end of the system.

The same reference characters refer to similar parts throughout the several figures and where similar details occur in different conveyor constructions, they are given the same reference characters.

In the embodiment illustrated in the drawing, I have shown the conveyors arranged in such a manner that the material travels substantially in a spiral. I have found that this is a convenient construction 90 to accomplish the desired results, for the reason that the same framework may be used for all of the conveyors of the separator proper and also for the reason that since the coal has a tendency due to the shape of its component parts to pass to the outer side of the conveyor to which it is delivered in each instance, each successive conveyor must bear a similar relation to its preceding elevator as every other bears to its preceding 95 elevator.

In the drawings, I have shown a conveyor A which delivers the unseparated mixture to the first of a series of twelve separating conveyors which I have designated B¹, B², B³, B⁴, B⁵, B⁶, B⁷, B⁸, B⁹, B¹⁰, B¹¹, B¹², respectively, all of the latter conveyors being 105 supported by the framework C.

Before describing in detail the operation of the separating mechanism as a whole, I 110 will describe in detail one of the conveyors. Since the details of construction of the sev-

eral conveyors, except as hereinafter noted, are substantially the same, only one conveyor will be thus described.

Referring particularly to Fig. 4, B² is a conveyor which is supported by the frame C and to which the coal and stone are delivered from the conveyor B¹. The belt 10 is supported by two large end rollers 11 and 12 which are pivotally supported in the sides 10 of the conveyor, one of which is shown at 13. A series of intermediate rollers 14 support the conveyor belt intermediate the end rollers 11 and 12 on the upper side. The lower side of the conveyor belt 10 is supported by rollers 15, 16, 17 and 18, the latter being supported preferably in a tank 19 containing water. A scraper 20 is suitably supported in position to scrape off particles of coal, stone and excess water where water 20 is used in the tank and to scrape off particles of stone and coal where the water is not used, the particles of stone and coal dropping into the tank 19, as well as the excess water when water is used.

Referring particularly to Fig. 6, 30 designates the end of the shaft which supports the roller 12 (Fig. 4) and to which the said roller 12 is secured. A worm gear 31 is mounted on the end of the shaft 30 and is 30 driven by a worm 32. The worm 32 is mounted on a shaft 33 which turns with the armature of a suitable electric motor supported by the frame C.

Referring particularly to Fig. 2, it will be seen that I have indicated the paths of travel of the minerals of different density by dash lines of different width. The paths of travel of the stone have been indicated by the heavy lines, the paths of travel of the slate by medium width lines and the paths of travel of the coal by the light lines.

In addition to the relative weight, the shapes of the stone, slate and coal have an effect on their distribution on the successive conveyors. The coal is more or less rounded as well as lighter than the stone and slate and for this reason, rolls to the far side while the stone and slate which are heavier and have flat surfaces have a tendency to remain 50 on the near sides of the respective successive conveyors.

In addition, there will be small particles of coal which will be carried from one conveyor to another with the slate. For the sake of clearness, this small coal has not been indicated. Its separation will be described later.

The mixture is delivered to the conveyor B¹ from the conveyor A, as it comes from the breakers, the pieces which make up the mixture being preferably of substantially the same size and being mixed so that neither the stone, slate nor coal occupy any particular relation to either edge of the conveyor. This is clearly shown by the illustra-

tion of the path of travel of the stone at 10, of the slate, at 11 and of the coal at 12, which paths are shown as bearing no particular relation to each other while on the conveyors A and B¹.

As the mixture leaves the end b¹ of the conveyor B¹, it will be noted that the paths 40, 41 and 42 take new positions upon the conveyor B², and that these paths tend to take a separated position, the coal tending to move to the outside or far side of the conveyor B², relative to the conveyor B¹, the stone tending to take a path on the inner or near side of the conveyor B² and the slate tending to take a position near the center line of the conveyor between the stone and coal.

As the ends b², B³, etc., are successively passed and delivery is made to the next succeeding conveyor, the tendency for the stone, slate and coal to separate, continues due to their relative densities until it has been sufficiently separated to warrant the delivery of the same. The number of conveyors necessary for this process to bring about such a result is dependent upon the conditions such as the amount of stone and slate in the coal and the shape, proportions, speed, etc., of the conveyors. In the present instance, I have assumed that the separation would be sufficiently complete to draw off part of the coal as it is delivered to the conveyor B⁶.

Accordingly, I have provided a chute 45 on the outside of the conveyor B⁶ and at a place opposite to the delivery end b⁶ of the conveyor B⁶. It will be noted from Fig. 3 that the coal as it tends to rest on the far or outside of the conveyor B⁶, will enter the chute 45 and be conducted to its proper place of storage. The edge of the chute extends 105 under the edge of the flexible belt of the conveyor B⁶ as indicated in dotted lines in Fig. 3.

In order to control at will the passage of coal to the chute 45, I provide a door or gate 46 which is shown on Figs. 3 and 6.

As the details of construction of the chute form no part of the present invention, the further details of the same will not be described. The showing of a chute at the side 115 of the conveyor B⁶ is merely illustrative. Although a chute may be provided at the side of any or all conveyors where the separated minerals are delivered, the showing and description of others would be needless repetition and perhaps confusing. Consequently such showing and description have been omitted.

In the present embodiment, I have shown the conveyor B¹¹ as being slightly modified 125 in that the outer side is capable of being placed at a slightly lower level than the inner side. The side of the frame of the conveyor B¹¹ opposite the delivery end of the conveyor B¹⁰, is cut away and a chute 47 130

provided which is similar in construction to the chute 45 attached to the conveyor B⁶.

I have made provision for changing the relative height between the outer and inner edges of the conveyor B¹¹. The inner edge of the conveyor is pivoted at its inner side as by hinged supports 50 which permit of the adjustment from a horizontal position to a position where the outer edge is some-
what lower than the inner edge. The outer side is supported by suitable adjusting means as the crank screw 51, which is threaded in the block 52 and carries at its lower end the flexible member 53 which is attached at
15 its lower end to the side of the conveyor. By this means, the adjustment of the angularity of the conveyor is accomplished.

I will now describe the purpose of this placing of the conveyor at an angle. If by
20 one or more chutes 45, the coal has been separated, from the mixture, then, it has been found to be desirable to remove the large pieces of rock from the conveyor, while still retaining the slate or flat pieces of stone.
25 This is for the reason that there is with the slate, as already indicated, a certain amount of very small flat pieces of coal which have fuel value and from which it is easier to separate the slate if the large round pieces of rock have been first removed.

When the rock, slate and very small coal are discharged from the conveyor B¹⁰, the slope of the conveyor belt toward the side, induces the round pieces of stone to roll
35 into the chute 47, while the flat pieces are carried upwardly to the conveyor B¹². The small pieces of coal stick to the conveyor B¹¹, more effectively when the latter is used in a wet condition as already described.

40 The slate, small rock and very small coal pass up the conveyor 12 and are delivered to the conveyor B¹³.

Referring now to Fig. 7, it will be clear that after passing down the conveyor B¹³,
45 the very small pieces of stone, slate and coal will pass between the end of the conveyor and the edge of the bottom of the chute B¹⁴ and will be delivered to the proper pile. The larger pieces of rock and slate
50 will pass over the opening between the conveyor and the end of the chute B¹⁴ and then conducted away to the desired place.

While I have described and shown embodiments of my invention in detail, I desire to have it understood that I do not limit myself to the exact showing and that modifications and changes may be made without departing from the spirit of my invention and within the scope of the appended claims.

60 Having described my invention, what I claim and desire to secure by Letters Patent, is:—

1. An apparatus for separating coal from stone and slate comprising a series of endless conveyors, each conveyor receiving ma-

terial from another conveyor being at a substantial angle thereto, the angle being measured in a horizontal plane, one of the conveyors having an opening opposite to the end of the conveyor delivering material thereto.

2. An apparatus for separating coal from stone and slate comprising a series of endless conveyors, each conveyor delivering to its successive conveyor and arranged at sub-
75 stantially a right angle thereto, a plurality of conveyors having openings opposite to the delivery ends of the respective preceding conveyors.

3. An apparatus for separating coal from stone and slate comprising a series of endless conveyors, each conveyor receiving material from another conveyor and being at a substantial angle thereto, a plurality of the conveyors having openings opposite the delivery ends of the respective preceding conveyors, the receiving end of each conveyor carrying the material away from the delivery end of the preceding conveyor in sub-
85 stantially the same direction relative to the position of the delivering conveyor and chutes opposite the openings.

4. An apparatus for separating coal from stone and slate comprising a series of endless conveyors, each conveyor receiving material from another conveyor being at a sub-
95 stantial angle thereto, and means for supporting one side of one of the conveyors at a lower level than its opposite side.

5. An apparatus for separating coal from stone and slate, comprising a series of endless conveyors, each arranged in an inclined position and driven so that the upper run thereof travels upwardly, the conveyors being arranged so that the longitudinal axis of each conveyor is transverse to the longitudinal axis of the next conveyor and so that each conveyor except the uppermost is adapted to discharge material from its upper end on to the lower end of the next conveyor, means for delivering material to be separated on to the lowermost conveyor, and means for discharging separated material from the uppermost conveyor.

6. An apparatus for separating coal from stone and slate, comprising a series of endless conveyors, each arranged in an inclined position and driven so that the upper run thereof travels upwardly, the conveyors being arranged so that vertical planes passing through the longitudinal axes of the conveyors form a closed geometrical figure and so that each of a plurality of conveyors is adapted to discharge material from its upper end on to the lower end of the next conveyor, means for delivering material to be separated on to the lowermost conveyor, and means for discharging separated material from the uppermost conveyor and also at a plurality of points respectively

opposite the discharge ends of a plurality of intermediate conveyors.

7. An apparatus for separating coal from stone and slate comprising a series of endless conveyors each arranged in an inclined position and driven so that the upper run thereof travels upwardly, the conveyors being arranged about a vertical axis with the discharge end of each conveyor, except the uppermost, over the lower end of the next succeeding conveyor, so that material deposited on the lowermost conveyor will be carried upwardly in a path winding about said axis, means for delivering material to be separated on to the lowermost conveyor and means for discharging separated material from the uppermost conveyor and also

at a point opposite the discharge end of an intermediate conveyor.

8. An apparatus for separating coal from stone and slate, comprising a series of endless conveyors each conveyor except the last of the series being arranged to discharge material transversely on to the next conveyor, means for delivering material to be separated on to the first conveyor of the series and means for discharging material from the last conveyor and also at a point opposite the discharge end of an intermediate conveyor.

In testimony whereof I affix my signature.

TOYOJIRO KATAYAMA.
